UNITED STATES PATENT OFFICE.

LOUIS BLUMENTHAL, OF BROOKLYN, NEW YORK.

KNIFE-SHARPENER FOR CLOTH-CUTTING MACHINES.

1,291,381.

Specification of Letters Patent. Patented Jan. 14, 1919.

Application filed May 6, 1918. Serial No. 232,728.

To all whom it may concern:

Be it known that I, LOUIS BLUMENTHAL, a citizen of the United States, residing at Brooklyn, in the county of Kings and State 5 of New York, have invented new and useful Improvements in Knife-Sharpener for Cloth-Cutting Machines, of which the following is a specification.

This invention relates to a device for 10 sharpening the lower cutting edge of a cloth cutting machine knife without removing it from the machine.

The invention is designed to provide a simple and efficient grinding device for co- 15 action with the lower portion of the knife which can readily be operated and accurately adjusted to center it relative to the lower bevel edge of the knife. The invention comprehends a pair of rotary emery 20 stone holders having universal adjustment to automatically position the holders for engagement with the bevel portions of the knife.

The invention is more fully described in 25 the following specifications and claims and illustrated in the accompanying drawing in which:

Figure 1 represents a side elevation showing the invention applied to the lower portion 30 of a cloth cutting machine.

Fig. 2 is a front elevation of the same.

Fig. 3 is a vertical section of a universal shaft.

Fig. 4 is a horizontal section taken along 35 the line 4-4 of Fig. 1.

Fig. 5 is a plan view of Fig. 1 showing the standard in section.

Fig. 6 is a perspective view of the centering clamp.

In this drawing the numeral 10 designates a channeled standard suitable for guiding a vertically arranged knife 11 having a lower cutting edge. The knife is reciprocated in the standard by mechanism which 40 is well known and needs no further description.

On the base plate 12 of the standard is arranged a frame 13 having a base extension 14 secured to the frame. The base is provided 45 with clamping members 15 having rear flanges 16 and a centering key or tongue 17 projecting from the forward portion of the clamp. A latch 18, best seen in Fig. 6,

is swingingly mounted on the rear of the flanges which when swung over the back of 55 the standard, as indicated in Fig. 1, will securely lock the clamp to the standard.

The key engages the channel when the clamp is in place and the clamping members or walls embrace the sides of the standard 60 to eliminate movement of the clamp. By having the key in engagement with the channel, as shown in Fig. 4, the clamp and the grinding devices carried by the clamp will be positioned in alinement with the knife. 65

The frame 13 supports a pair of shafts 19 having a universal joint 20 to permit the shafts to be arranged at an angle to each other. Each shaft is provided with a semi-circular holder 21 for carrying a block of 70 emery 22 secured to the holder. A key 23 coacting with a slot 24 in the holder will lock it to the shaft, but permit the holder to slide forward or back on the shaft. A coiled spring 25 will force the holder forward 75 toward the lower side portion of the knife.

The means for rotating the holders includes a pinion 26 fastened to one end of the universal shaft and a gear 27 mounted 80 on a driving shaft 28 operated by a crank 29 fixed to the shaft.

When the crank is operated, it transmits motion to the universal shaft and the pair of holders revolve in the same direction 85 with the shaft. Both holders are forced toward each other by the coiled springs, so that the emery blocks will coact with the bevel lower portion of the knife and the rotation of the holders grinds the same to 90 a fine point.

I claim:

1. A knife sharpening device comprising a universal jointed shaft, means for rotating the shaft, spring pressed semicircular abrasive holders slidingly mounted on the shaft for engagement with the lower portion of a knife, and means for alining the holders relative to the knife. 95

2. A knife sharpening device comprising 100 a standard and a frame, abrasive holders mounted on the frame for coaction with the lower portion of a knife, and a clamp connected to the standard for centering the holders relative to the knife. 105

3. A knife sharpening device comprising

a channel standard and a frame, abrasive holders mounted on the frame for coaction with the lower portion of a knife, and a clamp having a centering key for engagement with the channel to aline the holders with the knife.

In testimony whereof I have hereunto set

my hand in the presence of two subscribing witnesses.

LOUIS BLUMENTHAL.
